WEB REGISTERING DEVICE

William Hoppe, Longmeadow, and Franklin B. Roberts, West Springfield, Mass., assignors to National Bread Wrapping Machine Co., Springfield, Mass., a corporation of Massachusetts

Original application March 20, 1941, Serial No. 384,374. Divided and this application January 8, 1942, Serial No. 425,974

9 Claims. (Cl. 164—49)

This invention relates to registering devices for severing labels or the like in correct registration with printing or other indicia thereon. The present invention is a division of our prior application Serial No. 384,374, filed March 20, 1941.

It is one object of the invention to provide a registering apparatus of simple construction and low cost, which is for this reason capable of application to wrapping and labeling apparatus of a wide variety of types. A further object is to improve the positiveness with which the web is stopped for severance. Additional objects will appear from the following description and claims.

Referring to the drawings,

Fig. 1 is a vertical section through a web feeding and registering apparatus in accordance with the invention, taken on line 1—1 of Fig. 3;

Fig. 2 is similar section on line 2—2 of Fig. 3;

Fig. 3 is a top plan of the apparatus;

Fig. 4 is a detail showing the condition of the apparatus just before registration;

Fig. 5 is a detail showing the relation of the web and feeler at the same period as Fig. 4;

Fig. 6 is a similar view showing the act of registration; and

Fig. 7 is a similar view showing the release of the feed lock preliminary to the initiation of a fresh feeding movement.

The machine is driven from a shaft 28 which receives motion from any suitable source. A web *w* is supplied as from a suitable reel (not shown) and passes between plates 56, the function of which will appear later, and over a roll 57 which, when adjusted, remains in a fixed position. After leaving roll 57 the web passes between a driven roll 61 and a mating roll 62 carried on a swinging frame 63 pivoted on the machine at 64 and pressed towards the roll 61 by a tension spring 65. The rolls are preferably recessed at intervals as at 66 (Fig. 3), and are geared together at 67, 68, the latter of these gears meshing with a gear 69 to which are secured a driving ratchet 70 and a holding ratchet 71.

The rolls are driven by an oscillating pawl 75 carried upon a member 76 free to swing about the shaft 77 upon which the ratchets 70 and 71 and the gear 69 are mounted. To this member 76 is pivoted at 78 a link 79 pivoted at 80 to an arm 81 swinging on a shaft 82. A cam roll 83 on the arm 81 is held by a spring 84 against a cam 85 on the shaft 28 previously mentioned. The cam oscillates the pawl 75 in each cycle through such an arc as to rotate the feed rolls sufficiently to project the web upwardly beyond the rolls the length of one label. A pawl 86 swinging on a 55 predetermined point for causing the sprag to

stationary pivot 87 engages the feeding ratchet 70 to prevent retrograde movement of the feed rolls.

As the web rises above the feed rolls it passes between guide members 90, lying in the grooves 66, to direct it between a stationary cutter bar 91 and a movable cutter blade 92. The latter is pivoted at 93 to a rocker 94 swinging on a stationary pivot 95 and having an extension 96 bearing a cam roll 97. A cam 98 on shaft 28 causes periodic motion of the cutter to sever a blank from the web.

To keep the labels in constant registration with the cutting mechanism, so that the labels will be severed on the correct line with respect to the printing which they bear, they are preferably provided with perforations or notched edges through which may pass a pin 160 reciprocable through aligned holes 161 in the guide plates 56 (see Fig. 2). The pin is carried on an arm 162 filed on a cross shaft 163. This shaft also carries arm 164 (Fig. 1) drawn by a spring 165 to keep its end in engagement with an adjustable segmental cam 166 on the pawl carrier 76 which drives the label feed rolls 61, 62. The arm 164 also carries a multiple toothed pawl 167 or sprag which, when the arm 164 is permitted to rock by the passage of the pin through the web, grasps the holding ratchet as in Fig. 6 and stops further movement of the pawl carrier, which is driven only by the spring 84. The cam, which is adjustably mounted on the pawl carrier by a bolt and slot connection 168, is set so as to hold the pawl 167 out of contact with the holding ratchet 35 during the initial feeding of the label web, and to release the arm 164 to permit the pin 160 to rest on the web as the feeding motion approaches its end. When the pin finally drops into the hole in the paper the feed will stop instantly.

40 We claim:

1. A web registering device for intermittently driven feed rolls including a periodically operating, uni-directional, yielding drive for the feed rolls, a clamp one member of which is carried by said drive, and means responsive to the presence of web-borne indicia at a predetermined point for causing engagement of the members of the clamp.

2. A web registering device for intermittently driven feed rolls including a periodically operating, uni-directional, yielding drive for the feed rolls, a ratchet movable with said drive, a sprag movable to engage the ratchet, and means responsive to the presence of web-borne indicia at a predetermined point for causing the sprag to

engage the ratchet to interrupt its motion while the yielding drive ineffectively continues to exert its force.

3. A web registering device for intermittently driven feed rolls including a periodically operating, uni-directional, yielding drive for the feed rolls, a ratchet movable with said drive, a sprag movable to engage the ratchet, a feeler, means for moving the feeler periodically and yieldably into contact with the web during its advance, and mechanism actuated by the passage of the feeler through a perforation in the web to bring the sprag into contact with the ratchet to interrupt its motion while the yielding drive ineffectively continues to exert its force.

4. A web registering device for intermittently driven feed rolls including a drive gear coupled to the feed rolls, a spring coupled to the drive gear to rotate it in the feeding direction, a one-way clutch interposed between the spring and the drive gear, periodically acting mechanism for stretching the spring, a ratchet rotatable with the drive gear, a sprag mounted to engage the ratchet and stop the rotation of the feed rolls, and means responsive to the presence of web-borne indicia at a predetermined point for causing the sprag to engage the ratchet.

5. A web registering device for intermittently driven feed rolls including a drive gear coupled to the feed rolls, a spring coupled to the drive gear to rotate it in the feeding direction, a one-way clutch interposed between the spring and the drive gear, periodically acting mechanism for stretching the spring, a ratchet rotatable with the drive gear, a sprag mounted to engage the ratchet and stop the rotation of the feed rolls, a feeler, means for moving the feeler periodically and yieldably into contact with the web during its advance, and mechanism actuated by the passage of the feeler through a perforation in the web to bring the sprag into contact with the ratchet.

6. A web registering device for intermittently driven feed rolls including a drive gear coupled to the feed rolls, a spring coupled to the drive gear to rotate it in the feeding direction, a one-way clutch interposed between the spring and the drive gear, periodically acting mechanism for stretching the spring, a ratchet rotatable with the drive gear, a sprag mounted to engage the ratchet and stop the rotation of the feed rolls, a feeler, means for moving the feeler periodically and yieldably into contact with the web during its advance, including a cam angularly adjustable relative to the ratchet and coupled to the feeler to bring the feeler into contact with the web.

7. A web registering device for intermittently driven feed rolls including a drive gear coupled to the feed rolls, a first ratchet and a second ratchet coupled to the drive gear and having their teeth oppositely directed, a spring driven pawl periodically actuating the first ratchet, a second pawl engageable with the second ratchet, and means responsive to the presence of web-borne indicia at a predetermined point for causing the second pawl to engage the second ratchet.

8. A web registering device for intermittently driven feed rolls including a drive gear coupled to the feed rolls, a first ratchet and a second ratchet coupled to the drive gear and having their teeth oppositely directed, a spring driven pawl periodically actuating the first ratchet, a second pawl engageable with the second ratchet, a feeler connected to the second pawl for movement therewith, and yielding means for moving the feeler and second pawl towards the web at timed intervals, the second pawl being so positioned that it will make contact with the second ratchet only when the feeler passes through a perforation in the web.

9. A web registering mechanism for webs having spaced registering holes comprising web feed rolls, a unidirectional clutch one member of which is connected to drive said rolls, an oscillating member, a second member of said unidirectional clutch being fixed to said member, a cam carried by said oscillating member, a rocker engageable with said cam, a ratchet coupled to the feed rolls with its teeth in a direction opposing feeding movement of the rolls, driving means for the oscillating member yieldable in the direction of feeding movement, a feeler coupled to said rocker and engageable with the web, a support for the web having a recess in alignment with the feeler, and a pawl carried by the rocker and engageable with the ratchet when the feeler passes through a hole in the web, the cam being formed to release the feeler for yielding contact with the web prior to the alignment of a registering hole with the feeler.
